UNITED STATES PATENT OFFICE.

ALBERT C. WALLENSTEIN, OF CINCINNATI, OHIO, ASSIGNOR OF ONE-HALF TO WALTER MAYER, OF CINCINNATI, OHIO.

DESIGN FOR A RING.

Application filed April 12, 1924. Serial No. 9,240. Term of patent 14 years.

To all whom it may concern:

Be it known that I, ALBERT C. WALLENSTEIN, a citizen of the United States of America, and a resident of Cincinnati, Hamilton County, Ohio, have invented a new, original, and ornamental Design for a Ring, of which the following is a specification, reference being had to the accompanying drawing, forming part thereof.

Fig. 1 is a plan view of a ring, showing my new design.

Fig. 2 is a side elevation of a ring, showing my new design.

I claim:

The ornamental design for a ring, as shown.

ALBERT C. WALLENSTEIN.
